HINGED SECTION FOR FENCES, ETC.

Willie L. Seay, Paris, Tenn.

Application June 22, 1934, Serial No. 731,952

5 Claims. (Cl. 256—26)

This invention relates to articulated paneled sections such as may be provided to form a variety of structures, including fences, guards, seats and chairs.

5 The principal object of the invention is to provide a paneled section having a novel means for hingedly attaching it to another similar section so as to easily construct a large variety of structures embodying a number of forms.

10 One embodiment of a structure which may be easily provided by the novel section is a child's play yard fence, and which fence may be adjusted so as to define a large number of polygonal-shaped play yards.

15 An important object of the invention is to provide a plurality of sections which may be hingedly connected, with the hinged leaves offset laterally with respect to the sections so that compact bolting of the sections is permitted and so that the 20 assembled structure may be converted from one form to another, as from a play yard fence into a chair.

25 Another object is to provide a plurality of sections which may be hingedly connected together yet may be bound together into a rigid structure by means of a simple adjustment of the hinging device.

30 Still another object is to provide a plurality of sections which may be hingedly or rigidly connected together to form a structure, the change of the shape of the structure being easily effected, yet the hinging and connecting device is such that a small child, for instance, will not be able to disconnect the sections.

35 Another object is to provide an article as described which may be compactly folded so as to be convenient to carry or so as to occupy but limited space.

40 Still another object is to provide a plurality of sections which may be connected to form, for instance, a child's play yard fence, the construction of the sections being such that it will be difficult, if not impossible, for the fence to be tipped over.

45 Other objects and advantages of the invention will be apparent during the course of the following detailed description, taken in connection with the accompanying drawings, forming a part of this specification and in which drawings:—

50 Figure 1 is a perspective view of the novel sections arranged in substantially a straight line.

55 Figure 2 is an enlarged view, partly in section, of the adjacent ends of two sections, showing the hinging and fastening means.

Figure 3 is a perspective view of a portion of the means last mentioned.

Figure 4 is a side elevation of a plurality of the sections hinged together and folded.

Figure 5 is a plan view of four sections assembled to form a guard.

Figure 6 is a plan view of a plurality of sections assembled to define a play yard.

Figure 7 is a perspective view of a plurality of sections assembled to form a chair.

In the drawings, wherein for the purpose of illustration is shown only a preferred embodiment of the invention, the novel sections include rails which may be defined broadly as spaced apart top and bottom rails 10 and 11, these being substantially similar in shape and possessing outer faces 12, inner (facing) faces 13, end faces 14 and side faces 15. The end faces of the two rails are in substantially the same plane as are the side faces. Rigidly joining the two spaced apart rails 10 and 11 are a suitable number of spaced apart palings or bridging members 16. In the example shown, these palings are round and may have 20 their ends disposed within sockets in the rails or attached in any suitable manner. It will be noted that the end palings 16 are disposed well inwardly of the end faces 14 of the rails. Preferably, the rails and palings are of wood suitably 25 painted or enameled.

For the purpose of detachably coupling the sections together and in hinged relation, there is provided a hinging means including a plurality of hinge leaves 20, each of which preferably comprise a strap-like member of metal and possessing some resiliency, as will be more fully described in the specification. Each leaf includes an attaching portion 21 suitably perforated for the purpose of employing screws 22 or the like to 30 rigidly attach it to an outer face 12 of each rail, one leaf being disposed at each end of each rail, or four leaves to a section. At the outer end of each attaching portion, the leaf is continued as an offset portion 23, being offset with relation to the longitudinal axis of the attaching portion 22, and, consequently, the longitudinal axis of the rail to which the leaf is attached. In addition, a portion of the leaves are stepped as at 24 at their offset portions and inwardly of their free ends. 40 At their free ends, each leaf has a pintle perforation 25 and the surface of the leaf material, substantially encircling the perforation may be roughened or corrugated as at 26 for a purpose later brought out in detail. This roughing may be 45 upon only one face of the leaf or upon both upper and lower faces.

The leaves 20 are disposed upon the sections in the following arrangement. At one end of each 50

section, the offset portions 23 of the two leaves are not stepped and the offset portions (which, of course, are the portions of the leaves which project beyond the end faces 14 of the rails) both 5 project in the same direction so that the perforations 25 therein are substantially concentric. At the opposite end of the same section, the offset portions 23 of the other two leaves are stepped so that the offset portions 23 are nearer each 10 other than are the attaching portions 22 and the offset portions project so that their longitudinal axes substantially parallel the longitudinal axes of the other two leaves of the sections but they project to the other sides of the longitudinal 15 axes of the two rails. This is clearly brought out in Figure 5. It is preferred to attach the leaves to the outer faces 12 of the rails 10.

There is a common pintle 30 for each pair of 20 hinges, as shown in Figures 1 or 2, when the sections are assembled. This pintle 30 is a rod having a head 31 at one end and its free end screw threaded as at 32.

Cooperating with the corrugation 26, as a 25 means to selectively prevent pivoting of the sections upon their hinges, is a tubular member 35 of a length sufficient to extend from the facing faces of each leaf at its offset portion, and this tubular member has a bore to slidably accommodate the pintle 30 but not the head 31. The circumference of this tubular member 35 is preferably about that of the palings 16, for it may be said to represent the paling between each end paling of adjacent sections. Preferably adapted to screw upon the free-screw-threaded end of the 30 pintles, are suitable members, such as thumb or wing nuts 36.

In assembling the sections described, an easy 40 way is to lay one section flat upon a surface and then lay a second section upon the first so that, as is now apparent, two non-stepped leaves at one end of one section will have their perforations 45 concentric with the two stepped leaves at the end of the other section. With a tubular member 35 slipped between the facing leaves at top and bottom rails, and with its bore concentric with the perforations 25, the pintle 30 may be inserted thru the four perforations in the leaves and thru the bore of the tubular member 35 and the wing nut 36 screwed upon the protruding end of the pintle rod. This prevents the pintle from dropping out and hingedly connects the two sections. Other sections may be connected in the same manner, or the sections uncoupled, as is now apparent.

50 By further screwing the thumb nut 36, it will force the two adjacent overlapping offset portions of the leaves tightly together (since they possess some resiliency) and the leaf in contact with one end of the tubular member tightly against the tubular member which, in turn, will tightly engage at its opposite end the face of the adjacent leaf and this will press tightly its overlapping leaf, bringing the head 31 into tight engagement with the other face of the overlapping leaf. As a consequence, aided by the corrugations, the adjacent sections will be rigidly connected, so that the assembled sections may be disposed as desired to form a variety of polygonal-shaped play yards or the like.

55 By temporarily removing one pintle, nut, and tubular member, the sections may be collapsed as shown in Figure 4, or arranged, as a stove guard or the like, as shown in Figure 5. In Figure 7, the six sections making up the substantially hexagonal play yard of Figure 6, have been rearranged to

form a chair which will not collapse, since the sections may be rigidly connected, as well as hingedly connected together.

The frictional contact of the wing nut with the corrugations, prevents a child from working the wing nut loose, nor is it apt to become accidentally loosened from the pintle.

The overhanging offset portions of the leaves are disposed so as to permit ready temporary flexing of the leaves, and the tubular member, as 10 well shown in Figure 2.

The offsetting of a portion of the hinges enables a compact folding or collapsing of the sections and also permits the assembly of the sections into a variety of novel structures, such as 15 the chair shown in Figure 7. In addition, since there are portions extending beyond the general planes of the sections when set up (as in Figure 6, for instance), it is less likely that the structure may be tipped over. This is particularly important, when the sections are assembled 20 into a play yard fence.

There are but few separate parts to the assembly and since all may be carried by the collapsed structure (as in Figure 4), they are not 25 apt to become mislaid or lost.

Various changes may be made to the form of 30 invention herein shown and described, without departing from the spirit of the invention or the scope of the claims.

What is claimed is:

1. In a fence section, spaced apart upper and lower rails, a separate hinge leaf rigidly attached at one of its ends to each end of each rail, each of said leaves having a portion extending outwardly beyond the ends of said rails and being offset laterally from the longitudinal axes of said rails, each of said leaves being provided in its offset portion with a pintle perforation, with the leaves extending from the same end of said upper and lower rails substantially aligning and their perforations concentric, a common pintle 40 for each pair of aligning perforations and a single tubular spacer about each pintle and extending from leaf to leaf of each aligning pair of 45 leaves.

2. In an articulated portable fence, a plurality of fence sections having substantially like top and bottom rails; hinges connecting said sections together at the ends of only said top and bottom rails, each of said hinges possessing a slight resiliency and having overlapping portions with the faces thereof in contact with each other, each pair of hinges at adjacent ends of said sections having a common pintle; and means to 55 selectively prevent swinging of said sections upon their hinges, including a rigid tubular member disposed about each pintle and extending from one hinge to the other hinge of which said pintle forms a common pivot, and a member disposed upon the upper face of each uppermost leaf and adapted to bear upon said upper face.

3. In an articulated portable fence, a plurality of fence sections having substantially like top and bottom rails; hinges connecting said sections together at the ends of only said top and bottom rails, each of said hinges possessing a slight resiliency and having overlapping portions with the faces thereof in contact with each other, said contacting faces having corrugations there- 60 in, each pair of hinges at adjacent ends of said sections having a common pintle; and means co- 65 operating with said corrugations to selectively prevent swinging of said sections upon their hinges, including a rigid tubular member dis- 70 75

posed about each pintle and extending from one hinge to the other hinge of which said pintle forms a common pivot, and a member disposed upon the upper face of each uppermost leaf and adapted to bear upon said upper face.

4. In an articulated portable fence, a fence section having substantially like top and bottom rails; hinges connecting said sections together at the ends of only said top and bottom rails; each of said hinges possessing a slight resiliency and having overlapping portions with the faces thereof in contact with each other, said contacting faces having corrugations therein, each pair of hinges at adjacent ends of said sections having a common pintle with an enlargement upon the lower end thereof in contact with the outer face of the lowermost leaf and with screw threads about the upper end thereof; and means cooperating with said corrugations to selectively prevent swinging of said sections upon their hinges, including a rigid tubular member disposed about each pintle and extending from one hinge to the other hinge of which said pin-

tle forms a common pivot, and a member disposed upon the upper face of each uppermost leaf and adapted to bear upon said upper face, said last named member having screw threads cooperating with the screw threads of said pintle. 5

5. In an article of the class described, spaced apart substantially paralleling rails, a plurality of spaced apart bridging members extending from rail to rail and rigidly connected therewith, hinge leaves attached at the ends of each rail, each 10 leaf being strap-like in shape, each leaf further having a portion offset laterally from the longitudinal axis of the rail to which it is attached and provided in said offset portion with a pintle-receiving perforation the perforations in 15 the leaves extending from the same ends of said paralleling rails being concentric, a common pintle for each pair of aligning perforations and a single spacer about each pintle and extending from and bearing against the inner face of each 20 pair of leaves having their perforations concentric.
